UNITED STATES PATENT OFFICE.

HARRY C. GAMAGE, OF NEW YORK, N. Y., ASSIGNOR TO D. P. COMPANY, A CORPORATION OF NEW JERSEY.

DUST-GUARD FOR CAR-AXLE BOXES.

No. 918,528.

Specification of Letters Patent.

Patented April 20, 1909.

Application filed December 11, 1908. Serial No. 466,953.

To all whom it may concern:

Be it known that I, HARRY C. GAMAGE, a citizen of the United States, residing at New York, in the county of New York and State 5 of New York, have invented a certain new and useful Improvement in Dust-Guards for Car-Axle Boxes, of which the following is a specification.

The invention is a device for preventing 10 the entrance of dust into car axle journal boxes and consists, first, in a dust guard comprising two oppositely disposed elastic metal plates having openings for the reception of an axle, the said plates being connected only 15 at points near their edges and having their opposing faces elsewhere at a distance apart; also in the combination of the said guard with the car axle box, as hereinafter more particularly pointed out in the claim.

20 In the accompanying drawings—Figure 1 is a vertical section of a car axle journal box, showing my device in place. Fig. 2 is a transverse section on the line x , x , of Fig. 1. Figs. 3 and 4 respectively show in perspective the plates which are bolted together at their corners to form the dust guard, and Fig. 5 is an edge view of the dust guard separately and removed from the journal box.

Similar characters of reference indicate 30 like parts.

The journal box 1 is of the usual standard form, provided with a chamber 2 between its rear walls 3 and 4. In said walls are openings 5, 6, through which the car axle 7 passes, 35 the said openings being larger in diameter than the portion of the axle received in them.

8 and 9, Figs. 3 and 4, are plates of sheet metal, preferably steel, having openings 10 provided with circumferential flanges 11. The plates 8, 9 are rectangular in form. Each corner of each plate is first bent or inclined, as shown at 12, and then turned into a plane substantially parallel to the plane of 45 the main body of the plate, as shown at 13. The two plates 8, 9 are then placed together with their corner portions 13 abutting, as shown in Fig. 5, and are united into a single structure by rivets or bolts 14 passing 50 through said corner portions 13. In this way, a space 15 is formed between the separated inner faces of the plates 8, 9, to which access may be had through the opening between the plate edges. The plates 8, 9 be-

ing thus united form the dust guard A which 55 is introduced into the chamber 2 in the axle journal box. Before the said dust guard is inserted, a quantity of packing 16 is placed in the bottom of the chamber 2, and upon this packing the lower edge 17 of the dust 60 guard A rests, so that said packing forms an elastic supporting cushion for said dust guard. A quantity of packing may also be first put in position between the plates 8 and 9. 65

The axle 7 passes through the registering openings 10 with a loose fit, so that the actual weight of the dust guard A is borne by the supporting packing 16 and not by the axle, and in this way, possible wear of the 70 axle due to the superincumbent weight of the dust guard is prevented. More packing is then inserted through the upper opening between the plates 8, 9 until the space between the plates, and also the chamber 2, is filled, 75 as shown in Fig. 2. Plates 8, 9 are elastically compressible toward one another so that their outer faces bear resiliently against the walls of the chamber 2, and their pressure may be reinforced by constructing said plates 80 somewhat convex at their middle portions, as shown at 18, Fig. 5.

When the axle is moved transversely in the openings 5, 6 of the journal box, the dust guard A as a whole moves with the axle. 85 Conversely, if the journal box is moved transversely with respect to the axle, the walls of the box slide upon the outer faces of the dust guard A. In either case, a tight joint is maintained between the box walls and the 90 dust guard which effectually prevents the entrance of dust through the openings 5, 6 and into the interior of the box.

I claim:

95 In a dust guard for car axle boxes, two oppositely disposed quadrangular metal plates having openings for the reception of an axle, the said plates being bent toward one another and rigidly connected at their corners, and having their opposing faces elsewhere at a 100 distance apart.

In testimony whereof I have affixed my signature in presence of two witnesses.

HARRY C. GAMAGE.
